UNITED STATES PATENT OFFICE.

JULIUS BRENZINGER, OF FAIRFIELD, CONNECTICUT, ASSIGNOR TO SANITARY CAN MACHINERY COMPANY, OF ELLSWORTH, MAINE, A CORPORATION OF MAINE.

CAN-COVER.

1,287,206.

Specification of Letters Patent. Patented Dec. 10, 1918.

Application filed June 8, 1917. Serial No. 173,490.

To all whom it may concern:

Be it known that I, JULIUS BRENZINGER, a citizen of the United States, residing at Fairfield, in the county of Fairfield and State of Connecticut, have invented certain new and useful Improvements in Can-Covers, of which the following is a specification.

This invention relates generally to covers or tops for sheet-metal containers, with more particular reference to what are commonly known as "square cans", although they might more properly be called oblong with corners so decidedly rounded as to give them almost an oval shape.

Formerly, a filled can and its cover on top were adjusted by hand in the seaming mechanism of a so-called "heading" machine. Later, the demand for greater output capacity and consequently high speed of operation rendered necessary the provision of mechanism for automatically feeding the cans and covers to the seaming mechanism, and to simplify this operation the covers are stacked, in superposed relation, the lowermost or bottom cover being withdrawn and properly positioned on an advancing can in transit, gravity retaining the stack as a whole in such position that the bottom cover is always in position to be engaged by the cover-feeding mechanism.

These covers may be generally described as being "pan" shaped, having a depression which fits within the mouth of the can body and a projecting flange which is intercurled with the flange on the body to form a hermetic seam. In connection with so-called "round" cans, the edge of the flange of the cover is down-turned—easily and readily done in the stamping operation—and this really amounts to the first step of the intercurling operation and facilitates the action of the seaming rollers. However, it also serves to slightly space apart the stacked covers and permit withdrawal of the bottom cover by the cover-feeding device; otherwise, the covers would nest so closely that no form of tool could be relied upon to penetrate the stack between the bottom cover and the one next above in order to support the stack during removal of said bottom cover.

In connection with "square" cans, however, the sharper angle of curvature at the rounded corners renders it difficult to turn

down the flange edges of the cover in the stamping operation with the requisite uniformity. The edge of a "round" can cover is regular in contour, wherefore the degree, direction and effect of the forces of the stamping operation are substantially identical and the problem of die-forming the cover edges is simplified. In a "square" can cover, however, the edge includes both straight and curved portions, the metal of the former being merely bent over while in the latter it must be compressed, and this makes it exceedingly difficult to produce a perfectly uniform turned edge on the flange of a "square" can cover by a die-stamping operation. Furthermore, dies for this purpose must be exceedingly exact and accurate, and this not only adds to their initial cost but also to the expense of maintenance.

The principal object of the present invention is the provision of a "square" can cover having the usual depression and projecting flange, portions of the flange being so formed as to prevent nesting of the covers when stacked and hold them in such spaced relation to each other as to permit insertion of the separating tool between the bottom cover and the remainder of the stack to support the latter while the former was being withdrawn for superposition on the open can to be headed.

My invention will be readily understood by reference to the accompanying drawings, forming a part of this specification, in which—

Figure 1 is a plan view of a can cover embodying my invention;

Fig. 2 is a side view thereof;

Fig. 3 is a section taken substantially on the line 3—3 of Fig. 1, and

Fig. 4 is a side view of a plurality of my improved covers in stacked arrangement.

Referring now to the drawings in detail, numeral 7 designates what may be termed the depressed portion of a so-called "square" can cover, which is provided with the usual projecting flange 8 adapted to be intercurled with a corresponding flange on the body portion of the can to form the well-known double seam.

While these covers are more generally referred to as "square" can covers, implying rectilineal side and end edges, as a matter of fact these side and end edges have usually given a slight curvature, but for the pur-

poses of this description it may be assumed—for the time being—that the end edges 9 9 and the side edges 10 10 (prior to re-formation) are substantially straight, the corners 5 being rounded to conform to the rounded corners of the can body.

It will be apparent that this cover may readily be passed lengthwise between forming or bending rollers which operate to bend 10 or turn down portions of the opposite longer sides of the flange to form the depending lips 11 11. So far as the can heading operation is concerned, these lips probably perform no—or at least a negligible—useful 15 function, but it will be apparent that in the absence of these lips or their equivalents, these covers, when stacked in superposed arrangement, would nest so closely and snugly that it would be practically impossible 20 to slidably withdraw the lowermost cover. When these lips are provided, however, it will be apparent, as shown in Fig. 4, that when the covers are stacked they are so relatively spaced from each other that a 25 suitable separating and supporting tool may readily be so mounted and adjusted as to be made to dependably and invariably pass successively between each bottom cover, in turn, and the remainder of the stack and 30 support the latter during the operation of withdrawing said bottom cover, either slidably or by gravity through the removal of primary or initial supporting means—and this without disturbing the positional relationship 35 of the remaining covers, the entire stack, upon re-positioning of said primary or initial supporting means and withdrawal of said separating and supporting tool, falling to locate the "new" bottom cover for 40 repetition of the separating and feeding operations.

As hereinbefore suggested, a perfectly uniform turned-down flange edge facilitates—rather than impairs—the seaming operation, but lack of substantially perfect uniformity is likely to result in the formation of an imperfect seam. Therefore, packers have objected to "square" can covers having a continuous turned-down flange 45 edge, and have preferred the flat flange. However, as I turn down only substantially

straight portions of the flange edge, the desired uniformity is insured throughout the whole extent of the turned-down portions and a practically perfect seam may readily be formed.

While to facilitate description I have referred to the end edges 9 9 and the side edges 10 10 as being straight edges, they are really slightly curved. The slight curvature of the side edges 10 10 is of practical advantage to me in the carrying out of my invention, for if these edges were rectilineal, in passing the cover between edge-turning rollers the flange-edge would not only have to be down-turned throughout its entire length but the down-turned portion would necessarily slightly encroach upon the rounded corners at each end, whereas when this edge is curved the major middle portion only thereof is down-turned, sufficient in extent to prevent nesting but insufficient to prevent the formation of a substantially perfect seam.

I do not claim patentable novelty for a can cover having a continuous down-turned flange edge, but what I do claim is—

1. A cover or top of sheet-metal containers having comparatively straight side and end edges and rounded corners, and having a continuous flange to be intercurled with a flange on the body portion of the container, opposite comparatively straight edges only being down-turned to prevent nesting of the covers when assembled in stacked arrangement. 8

2. An oblong cover of top for sheet-metal containers having comparatively straight side and end edges and rounded corners, and having a continuous flange adapted to be intercurled with the flange on the body portion of the container, the flanged edges of the longer sides only being down-turned to prevent nesting of the covers when assembled in stacked arrangement. 9

In testimony of the foregoing, I have hereunto set my hand in the presence of two witnesses.

JULIUS BRENZINGER.
